UNITED STATES PATENT OFFICE.

ERNEST C. SPRINGER, OF KANSAS CITY, MISSOURI.

GRINDING AND POLISHING MACHINE.

1,405,454.

Specification of Letters Patent.

Patented Feb. 7, 1922.

Application filed July 29, 1920. Serial No. 399,859.

To all whom it may concern:

Be it known that I, ERNEST C. SPRINGER, a citizen of the United States, residing at Kansas City, in the county of Jackson and 5 State of Missouri, have invented certain new and useful Improvements in Grinding and Polishing Machines, of which the following is a specification.

My invention relates to machines for 10 grinding and polishing cultivator disks, cultivator shovels, different kinds of tools, etc., and my object is to provide a new and useful machine of this character whereby cultivator disks and shovels of different sizes can be 15 quickly ground and polished and tools readily and accurately sharpened.

In order that the invention may be readily understood, reference will now be had to the accompanying drawings, in which:

20 Fig. 1 is a plan view of the machine with a cultivator disk in position to be sharpened.

Fig. 2 is a front elevation of a portion of the mechanism disclosed by Fig. 1.

25 Fig. 3 is a vertical cross section on line III—III of Fig. 2.

Fig. 4 is an enlarged irregular section on line IV—IV of Fig. 1.

Fig. 5 is a vertical section on line V—V of 30 Fig. 4.

Fig. 6 is a rear elevation of the grinding wheel and associated parts.

Fig. 7 is a broken plan view of a tool rest and guide associated with the grinding wheel.

35 Fig. 8 is a detail perspective view of a slidable head whereby certain parts of mechanism may be adjusted to accommodate disks of different sizes.

Fig. 9 is a detail perspective view of a bracket which is associated with the slidable 40 head to coact therewith in adjusting certain parts of the mechanism to accommodate disks of different sizes.

Fig. 10 is a longitudinal sectional view of an extensible shaft and associated parts.

45 Referring now to the various parts in detail, 2 designates any suitable grinding wheel consisting of emery or other abrasive material. Said grinding wheel 2 is fixedly mounted upon a drive shaft 4 journaled in the upper 50 ends of standards 6 and provided with a small fixedly mounted pulley 7 adapted to be driven by a belt, not shown. The drive shaft 4 is also provided with a small fixedly mounted pulley 8, for driving a large pulley

55 10 through the intermediacy of a belt 12. A safety guard 11 supported by a bracket 13

from one of the standards 6, covers a portion of the grinding wheel 2.

The large pulley 10 is fixedly mounted upon a shaft 14 which may be manually driven by 60 a crank 16, when other power is not available for driving the pulley 7. The shaft 14 is journaled in the upper ends of standards 20 and provided with a fixedly mounted bevel gear 22, which drives a bevel gear 24 65 fixed upon a shaft 26 arranged at an angle to the shaft 14 and journaled in the upper ends of standards 28.

The shaft 26 is provided with a small fixedly mounted pulley 30, which drives a 70 large pulley 32 through the intermediacy of a belt 34. The large pulley 32 is fixedly mounted upon a counter shaft 36 journaled in brackets 38 secured to a horizontal support consisting in the present instance of two 75 parallel bars 40. As disclosed more clearly on Fig. 1, the counter shaft 36 and the bars 40 are arranged parallel to the shaft 26. The bars 40 are secured by set screws 42 in the upper ends of a pair of standards 44, which 80 like the standards 6, 20 and 28, are fixed at their lower ends to a base 46 which may be supported on a work bench or legs (not shown).

48 designates a slidable head which is 85 mounted upon the bars 40. Said slidable head 48 has a vertical slot 50 through which the bars 40 extend, and a horizontal slot 52 in which a bracket 54 is slidably mounted. The slidable head 48 is secured at any point 90 of its adjustment upon the bars 40 by a set screw 56, and the bracket 54 is secured at any point of its adjustment by a set screw 58 which like the set screw 56 is threaded in the upper portion of said slidable head 48. 95

60 designates a yoke provided at one side with lugs 62 pivotally mounted upon a bolt 64 extending through a boss 66 formed integral with one end of the bracket 54.

68 designates a shaft which is journaled 100 in the yoke 60 and provided with a conical bushing 70, held in place by a set screw 72. The bushing 70 is adapted to project through the axial opening B in the cultivator disk A and thus hold said disk in concentric relation to the shaft 68. The disk A is firmly held upon the bushing 70, so that it will rotate therewith, by means of a clamp member 75 which fits freely over the outer end of the shaft 68 and is forced into engagement with 105 the adjacent side of the disk A by a nut 74 threaded upon the outer end of the shaft 68.

The clamp member 75 is provided with a plurality of thumb screws 76, which coact with said clamp member 75 in holding the disk A in proper axial position upon the 5 bushing 70.

The shaft 68 is provided with a fixedly mounted cog wheel 78, which is driven by a pinion 80 fixedly mounted upon a short shaft 82, connected at one end to a universal coupling 84 driven by an extensible shaft consisting of members 86 and 88. The member 86 is slidably mounted in the tubular member 88 which is journaled in bearings 90 on a bracket 92 secured by bolts 94 to the under- 10 side of the slidable head 48. The shaft member 88 drives the member 86 through a groove-and-feather connection 96 and is provided with a fixedly mounted bevel gear 98, which is driven by a pinion 100 slidably 15 mounted upon the shaft 36 and driven thereby through the intermediacy of a groove-and-feather connection 102.

When it is desired to stop the disk A without stopping the grinding wheel 2, the pinion 100 is thrown out of engagement with the 20 large bevel gear 98 as disclosed by dotted lines Fig. 1, through the intermediacy of a shift lever 104 having a shank 106 pivotally mounted upon the shaft 36 at a point between 25 the hub of the pinion 100 and a collar 108 adjustably secured to the shaft 36 by a set screw 110. The shift lever 104 is held in either of its adjusted positions by engaging its shank 106 against either side of a fork 30 110, fixed to one end of an arm 114 formed integral with the bracket 92.

The disk A is moved in and out of engagement with the grinding wheel 2 by swinging the yoke 60 upon the bolt 64 40 through the intermediacy of an arm 116, which is secured by suitable means such as screws 118 to lugs 120 integral with said yoke 60.

The arm 116 is controlled by a hand lever 45 121 pivotally mounted upon the bolt 64 and provided with a handle 122. Said lever 121 is provided with a pivotally-mounted member 124 through the upturned end of which a rod 126 freely extends, said rod being 50 connected at one end to the arm 116 and provided at its opposite threaded end with a wing nut 128, whereby the arm 116 may be adjusted toward or away from the member 124 to tension a coil spring 130 interposed 55 between the upturned end of said member 124 and a washer 132 mounted on the rod 126 and bearing against the arm 116.

The lever 121 is held at any point of its 60 pivotal adjustment by a set screw 134 threaded through said lever 121 and engaging a segment 136, having a downwardly extending arm 138 secured by a screw 140 to the upper boss 66 of the bracket 54.

In addition to the mechanism above de- 65 scribed for sharpening and polishing disks

of different sizes, I also provide means for grinding drill bits and other tools as herein-after described. 146 designates a bracket adjustably secured by bolts 148 to a web 150 uniting the standards 6. The upper 70 portion of said bracket 146 is provided with a tool rest 152 adjustably secured in place by a bolt 154 extending through a slot 156 in the upper portion of the bracket 146. By loosening the bolt 154 the tool rest 152 can 75 be adjusted toward or away from the grinding wheel 2. The tool rest 152 is provided at its upper surface with a guide 158 for holding certain kinds of tools as drill bits D in proper relation to the periphery of 80 the grinding wheel 2.

The operation briefly stated is as follows: The slidable head 48 is adjusted longitudinally of the bars 40 to accommodate disks of different diameters to insure their margins being brought opposite the periphery of the grinding wheel 2. The bracket 54 is then adjusted in the head 48 to move the disk A laterally in proper relation to the grinding wheel 2, the universal coupling 84 90 and the members 86 and 88 of the extensible shaft readily yielding to permit of such adjustment. The disk A is then swung into contact with the periphery of the grinding wheel 2 by swinging the lever 121 in the direction of the dotted arrow, Fig. 1. After the disk A has been brought into contact with the grinding wheel 2 under the desired pressure, the lever 121 is secured to the segment 136 through the intermediacy of the 95 set screw 134. Rotary motion is then imparted to the grinding wheel 2 through the intermediacy of the shaft 4 which is driven either from the pulley 7, or the shaft 14 through the intermediacy of the pulleys 8 100 and 10 and the belt 12. Rotary motion is imparted to the disk A from the shaft 14 through the intervening gearing which is, preferably, proportioned to drive said disk A at a slower speed than the grinding wheel 110 2, so that the grinding operation may be rapid and uniform. As the disk A is yieldably held in engagement with the grinding wheel 2 through the intermediacy of the spring 30 and associated parts, said disk A 115 is free to swing laterally due to any irregularities in its margin and hence no damage will be caused to said disk A or the grinding wheel 2. The universal coupling and the extensible shaft consisting of the members 86 120 and 88, readily yield and accommodate themselves to such lateral movement of the disk A, and continue to drive the same through the intervening gearing above described. After the disk A has been sharpened the set 125 screw 134 is disengaged by the segment 136, and the lever 121 is swung in a direction opposite to the dotted arrow Fig. 1, to swing the disk A out of engagement with the grinding wheel 2. The nut 74 is then re- 130

5 moved, so that the disk A can be taken off the cone 70. If the disk A is to be polished it is left upon the conical member 70 and the head 48 is moved to the left during the polishing operation to carry the axis of the disk toward the grinding wheel 2.

Having thus described my invention, what I claim and desire to secure by Letters Patent, is:

- 10 1. In a machine of the character described, a grinding wheel, means for driving said grinding wheel, means for yieldably holding a disk in engagement with said grinding wheel to permit lateral movement of said disk during the grinding operation, a universal coupling, an extensible shaft associated with said universal coupling and the disk to drive the latter and permit lateral movement thereof, and means for driving 20 said extensible shaft.
2. In a mechanism of the character described, means for sharpening a disk, a rotary support for said disk, an adjustably mounted yoke in which said rotary support 25 is mounted, manual means yieldably connected to said yoke to adjust the same and cause it to move the disk in or out of engagement with the sharpening means, means for securing said manual means at any point of 30 its adjustment, a spring interposed between said manual means and the yoke so that the same may yield under inequalities in the disk surface being sharpened, a member associated with the yoke and the manual means 35 to effect longitudinal adjustment of the rotary disk support, and a movable head carrying said member to effect lateral adjustment of the rotary disk support.
3. In a mechanism of the character de- 40 scribed, means for sharpening a disk, a rotary support for said disk, an adjustably mounted yoke in which said rotary support

is mounted, manual means yieldably connected to said yoke to adjust the same and cause it to move the disk in or out of engagement with the sharpening means, means for 45 securing said manual means at any point of its adjustment, a spring interposed between said manual means and the yoke so that the same may yield under inequalities in the 50 disk surface being sharpened, a member associated with the yoke and the manual means to effect longitudinal adjustment of the rotary disk support, a movable head carrying said member to effect lateral adjustment of 55 the rotary disk support, a bar upon which said head is mounted, and a support for said bar.

4. In a mechanism of the character described, means for sharpening a disk, a rotary support for said disk, an adjustably mounted yoke in which said rotary support is mounted, manual means yieldably connected to said yoke to adjust the same and cause it to move the disk in or out of engagement with the sharpening means, means for 60 securing said manual means at any point of its adjustment, a spring interposed between said manual means and the yoke so that the same may yield under inequalities in the 65 disk surface being sharpened, a member associated with the yoke and the manual means to effect longitudinal adjustment of the rotary disk support, an extensible shaft yieldably geared to the rotary disk support to 70 drive the same in any of its adjusted positions, and adjustable gearing for driving 75 said extensible shaft.

In testimony whereof I affix my signature, in the presence of two witnesses.

ERNEST C. SPRINGER.
